UNITED STATES PATENT OFFICE.

FOSTER CARTER, OF SHREVEPORT, LOUISIANA.

FAN ATTACHMENT FOR SEWING-MACHINES.

SPECIFICATION forming part of Letters Patent No. 338,925, dated March 30, 1886.

Application filed January 26, 1886. Serial No. 189,817. (No model.)

To all whom it may concern:

Be it known that I, FOSTER CARTER, a citizen of the United States, residing at Shreveport, in the parish of Caddo, State of Louisiana, have invented certain new and useful Improvements in Fan Attachments for Sewing-Machines of which the following is a specification, reference being had therein to the accompanying drawings.

- 10 My invention relates to fan attachments for sewing-machines; and it consists in the construction and novel combination of parts, as will be hereinafter fully described, and particularly pointed out in the claims.
- 15 In the accompanying drawings, Figure 1 is a view in perspective of my fan attachment connected to the sewing-machine and with the treadle of the machine in a manner ready to be operated. Fig. 2 is a detail perspective
- 20 view of the fan-post, cross-arm, fan-arm, fan, retracting-spring, and operating-cord, and Fig. 3 a perspective detail view of the bracket bar or arm by which the operating-cord is connected to the treadle of the sewing-machine.
- 25 Referring by letters to the accompanying drawings, A designates the sewing-machine, which may be of any of the well-known patterns of treadle-operated machines, and B is the treadle of the same, and B' is the table of the sewing-machine. The fan-post C is provided near its lower end with two jaws, D D', the lower one, D', of which is provided with a thumb-screw, E, by which the fan-post is securely fastened to the rear edge of the machine-table when
- 30 it is desired to use the fan attachment. Near its upper end the fan-post is provided with a cross-arm, F, which is stationary, and which, when the attachment is in place, is parallel with the rear edge of the table-top. Pivoted
- 35 upon a pin or bearing, G, at the upper end of the fan-shaft is the fan-arm H, which is provided at its forward end, I, with a horizontally-adjustable fan, J, the handle J' of which is held in a socket in the end of the pivoted

fan-arm by a set-screw, K, and is adjustable 45 in its seat, so that it may be projected or retracted, as may be desired. The other end of the fan-arm H is connected by a retracting-spring, L, to the end of the cross-arm F nearest the end N of the fan-arm. The operating-cord O is connected to the rear end of the fan-arm H, and runs over a pulley, P, at the end Q of the cross-arm F farthest from the retracting-spring, and runs down to the rear end of the bracket-bar S, to the rear end of which it 55 is connected. S' are the brackets for said bar S.

From the foregoing description, taken in connection with the drawings, it will be readily seen that when the treadle of the sewing-machine shall be operated the fan-arm will be 60 oscillated and the fan thereby be put in operation, so that the operator's hands may be devoted exclusively to the work and the sewing-machine.

Having thus described my invention, what I 65 claim as new, and desire to secure by Letters Patent of the United States, is—

1. The combination, with the fan-standard having the clamps near its lower end, and the cross-arm F near its upper end, of the fan-arm 70 and fan, the spring connecting the cross-arm and fan-arm, the pulley on the cross-arm, the operating-cord, and the bracket-bar S, substantially as specified.

2. The combination, with a sewing-machine, 75 of the fan-standard provided with the attaching-clamp near its lower end and the pivot-pin in its upper end, of the rigid cross-arm with pulley at one end, the pivoted fan-arm, the adjustable fan at the end of the fan-arm, 80 the retracting-spring, and the operating-cord and bracket-bar S, substantially as specified.

In testimony whereof I affix my signature in presence of two witnesses.

FOSTER CARTER.
